PLASTIC COATED SHEET MATERIAL

Richard A. Mazur, McFarland, Wis., assignor to Uniroyal,
Inc., a corporation of New Jersey

Filed Mar. 23, 1966, Ser. No. 1,605

Term of patent 14 years

(Cl. D87—3)

The figure of the drawing is a plan view of a plastic coated sheet material showing my new design.

A single repeat of the design is enclosed within the quadrangle bounded by the broken lines in the figure of the drawing.

I claim:

The ornamental design for a plastic coated sheet material, as shown and described.
